DESIGN FOR A LIGHTING UNIT

Alphonse F. Pieper, Brighton, N. Y.

Application March 19, 1940, Serial No. 91,079

Term of patent 14 years

To all whom it may concern:

Be it known that I, Alphonse F. Pieper, a citizen of the United States, residing at Brighton, in the county of Monroe and State of New York, have invented a new, original, and ornamental Design for a Lighting Unit, of which the following is a specification, reference being had to the accompanying drawing, forming part thereof.

Fig. 1 is a perspective view of the lighting unit, showing my new design; and

Fig. 2 is a perspective view inverted from the showing in Fig. 1.

I claim:

The ornamental design for a lighting unit, substantially as shown.

ALPHONSE F. PIEPER.
